TILLER HOUSING

John W. Davies III, Plymouth, Wis., assignor to Gilson Bros. Co., Plymouth, Wis., a corporation of Wisconsin

Filed Dec. 16, 1965, Ser. No. 218

Term of patent 14 years

(Cl. D40—1)

FIG. 1 is a perspective view of a tiller housing embodying the present invention as applied to a rotary tiller.

FIG. 2 is a plan view of the tiller housing, per se.

FIG. 3 is an end view of the tiller housing, per se.

FIG. 4 is a perspective view of the tiller housing per se.

FIG. 5 is a fragmentary cross section taken along the line 5—5 of FIG. 2.

FIG. 6 is a cross section taken along the line 6—6 of FIG. 2.

The dotted line showing is for illustrative purposes only.

I claim:

The ornamental design for a tiller housing, as shown and described.
